UNITED STATES PATENT OFFICE

114,069

DESIGN FOR A SAVINGS BANK OR SIMILAR ARTICLE

Edwin Klahn, New York, N. Y., assignor to Adolf
C. Blechner, New York, N. Y.

Application October 7, 1938, Serial No. 80,311

Term of patent 7 years

To all whom it may concern:

Be it known that I, Edwin Klahn, a citizen of Germany, residing in the city of New York, county of New York, and State of New York, have invented a new, original, and ornamental Design for a Savings Bank or Similar Article, of which the following is a specification, reference being had to the accompanying drawing, forming a part thereof.

I claim:

The ornamental design for a savings bank or similar article as shown.

EDWIN KLAHN.
